[57] CLAIM

The ornamental design for a golf club head cover, as shown and described.

DESCRIPTION

FIG. 1 is a view in perspective showing my new design for a golf club head cover;

FIG. 2 is a view in side elevation, as seen from the left in FIG. 1;

FIG. 3 is a view in side elevation, as seen from the right in FIG. 2;

FIG. 4 is a view in side elevation, as seen from the left in FIG. 2;

FIG. 5 is a view in side elevation as seen from the side opposite that shown in FIG. 2;

FIG. 6 is a view in top plan;

FIG. 7 is a view is bottom plan;

FIG. 8 is a view in perspective, with the golf club head cover of my invention open for mounting on a golf club;

FIG. 9 is a view in perspective of a second embodiment showing my new design for a golf club head cover;

FIG. 10 is a view in side elevation, as seen from the left in FIG. 9;

FIG. 11 is a view in side elevation, as seen from the right in FIG. 10;

FIG. 12 is a view in side elevation, as seen from the left in FIG. 10;

FIG. 13 is a view in side elevation as seen from the side opposite that shown in FIG. 10;

FIG. 14 is a view in top plan;

FIG. 15 is a view is bottom plan, and,

FIG. 16 is a view in perspective, with the golf club head cover of my invention open for mounting on a golf club.
